UNITED STATES PATENT OFFICE.

LYMAN JANQUART, OF MENOMINEE, MICHIGAN.

BEAN-SNIPPER.

1,115,546.

Specification of Letters Patent. Patented Nov. 3, 1914.

Application filed March 5, 1913. Serial No. 752,239.

To all whom it may concern:

Be it known that I, LYMAN JANQUART, a citizen of the United States, residing at Menominee, in the county of Menominee and 5 State of Michigan, have invented a new and useful Bean-Snpper, of which the following is a specification.

This invention relates to bean snippers and is designed more particularly as an improvement upon the structure disclosed in 10 an application filed by me on July 25, 1912, said application bearing Serial No. 711,514.

The principal object of the present invention is to provide improved means for feeding 15 the beans to the cutting devices, and to otherwise improve upon machines of this character such as heretofore constructed.

With the foregoing and other objects in view which will appear as the description 20 proceeds, the invention resides in the combination of parts and in the details of construction hereinafter described and claimed, it being understood that changes in the precise embodiment of the invention herein disclosed, can be made within the scope of what 25 is claimed, without departing from the spirit of the invention.

In the accompanying drawings the preferred form of the invention has been shown. 30 In said drawings:—Figure 1 is a view partly in side elevation and partly in section of one end portion of a machine embodying the present improvements. Fig. 2 is a plan view of the structure shown in Fig. 35 1, only one side portion of the machine being shown. Fig. 3 is an end elevation of a portion of the feed hopper and adjacent parts.

Referring to the figures by characters of 40 reference, 1 designates a table which can be of any desired proportions, the same being provided at its ends with supports 2 suitably braced as at 3. Inasmuch as the supports at both ends of the table can be the 45 same, it has been deemed necessary to illustrate only one end of the table, said end being the feed end.

An endless belt 5 may be arranged with 50 its upper flight extending over the table but flush therewith and any suitable means may be provided for actuating the belt. This structure, however, does not constitute any part of the present invention, but has been fully disclosed in my application hereinbefore mentioned.

Extending downwardly from the feed end

of the table 1 is a guide plate 7 to which a hopper 8 is fixedly connected. This plate is connected to the table by a flexible metal sheet 20 and any suitable means may be provided for locking the plate 7 at any desired angle to the brace 3. For example, an arcuate arm 9 may be fixedly connected to the brace 3 and may be provided with a series of openings 10 any one of which is adapted to receive a holding pin 11 extending laterally from the hopper 8. Thus it will be seen that plate 7 can be locked against movement relative to the support. Hopper 8 has its bottom 12 pivotally mounted at 13 and the lower end of said bottom is supported by a stop 14. This stop is in the form of a small plate secured to one side of the hopper 8 and having its free end extended under the side portion of the bottom 12, as 60 65 70 75 shown particularly in Figs. 2 and 3.

A finger 15 extends from the movable bottom 12 and into the path of a series of tappets 16 extending laterally from a sprocket 17. This sprocket is secured to a shaft 18 80 which is journaled in blocks 18' secured upon the bottom portion of the braces 3. Any desired number of these sprockets 17 may be provided and each sprocket engages an endless chain 19. These endless chains 85 are parallel and extend upwardly along guide plate 7. This plate and sheet 20 constitute an extension or continuation of the table. From the plate 7 the chains 19 extend longitudinally along the tops of the 90 upstanding sides 25 of table 1 and across the diagonally disposed upper flight of belt 5 and then pass under the far end of the table and return to the sprockets 17, it being understood that additional sprockets may be 95 provided wherever desired so as to properly guide the chains. As shown in Fig. 1 hangers 21 can be extended from the table so as to adjustably support a roller 22 or the like having trunnions 23 which are mounted in 100 vertical slots 24 in the hangers. This roller acts as an adjustable tightener for the chains while permitting the plate 7 to swing about its pivot.

The chains 19 are provided with spaced 105 parallel slats 26 which are adapted to slide upwardly along the sheet 20 and thence longitudinally along the table 1 between the sides 25. These slats are spaced apart a sufficient distance to receive any desired number 110 of beans between them. One of the sides 25 is cut away directly above the belt

5, as shown at 27 and arranged longitudinally within this cut-away portion is a gage bar 28.

Secured to the sides 25 so as to extend partly across the inner portion of the opening 27 is a snipping blade 31.

It is to be understood that in operation the beans to be snipped are placed in hopper 8 and the mechanism set in motion. As 10 the shaft 18 rotates the chains 19 are set in motion and the slats 26 are thus caused to slide upwardly along plate 7 and onto the table 1. Beans will gravitate along the bottom 12 so as to partly fill the spaces between 15 the slats and this movement of beans into the said spaces will be facilitated by the agitation of the bottom 12. This agitation is set up by the tappets 16 coming successively into contact with the finger 15. 20 As the beans are brought into position above the belt 5, said belt, which is moving obliquely across the table, will drag the beans transversely of the table so that as they are brought opposite the space 27, the 25 beans will be projected at one end into said space and against the gage bar 28. As the slats continue to drag the beans forwardly, said ends of the means will be brought against the knife 31 and the ends snipped 30 by the edge thereof coöperating with the ends of the slats. The beans will then be drawn past the knife and longitudinally of the table and, by duplicating the mechanism adjacent the discharge end of the table, so 35 that the beans will be shifted toward the opposite side thereof, the other ends of the beans can be snipped off in the same manner. Such an arrangement for successively cutting off the ends of the beans has been 40 disclosed in my application hereinbefore referred to.

By mounting the hopper 18 for angular adjustment, the same can be arranged for use in connection with beans of different

sizes, it being found that beans of one size 45 will gravitate more rapidly into the spaces between the slats than will beans of other sizes and it is therefore desirable to adjust the hopper 8 so as to adapt the machine for use in connection with beans of different 50 sizes.

What is claimed is:—

1. A machine of the class described including a hopper having a movable bottom, a conveyer extending upwardly through the 55 hopper, and means actuated by the conveyer for agitating the bottom of the hopper to direct the contents of said hopper onto the conveyer.

2. A machine of the class described including a table having a downwardly inclined extension at its feed end, a hopper on said extension and mounted for angular adjustment relative to the table, an endless conveyer extending through the hopper and 65 along said extension and longitudinally of the table, said conveyer including spaced slats, and means for agitating the bottom of the hopper to direct beans into the spaces between the slats. 70

3. A machine of the class described including a hopper mounted for angular adjustment, an endless conveyer movable upwardly through the hopper and including spaced slats, said hopper being provided with a movable bottom inclined downwardly toward the conveyer, and means operated by the conveyer for agitating the bottom to direct the contents of the hopper into the spaces between the slats. 75

In testimony that I claim the foregoing as my own, I have hereto affixed my signature in the presence of two witnesses.

LYMAN JANQUART.
